UNITED STATES PATENT OFFICE

101,584

DESIGN FOR A PASTRY CUTTER

Ada M. Hoffman, Los Angeles, Calif.

Application August 21, 1935, Serial No. 58,234

Term of patent 7 years

To all whom it may concern:

Be it known that I, Ada M. Hoffman, a citizen of the United States, residing in the city and county of Los Angeles, State of California, have invented a new, original, and ornamental Design for a Pastry Cutter, of which the following is a specification, reference being had to the accompanying drawing forming a part thereof:

The figure is a perspective view of the pastry cutter showing my new design.

The bottom of the pastry cutter is open.

I claim:

The ornamental design for a pastry cutter, as shown and described.

ADA M. HOFFMAN.
